ATTACHMENT FOR AUTOGRAPHIC REGISTER

John E. Euth, Chicago, Ill., assignor to Uarco,
Incorporated, a corporation of Illinois
Filed Dec. 21, 1961, Ser. No. 161,011
5 Claims. (Cl. 282—15)

This invention relates to an attachment for an autographic register and more particularly to an attachment designed to detect and prevent tampering with the normal advancement of register forms.

Many retail transactions are recorded today on the conventional autographic register. Frequently attempts are made to destroy the store owner's carbon copy of a transaction of sale. In this manner a customer may have a receipt for payment of goods on hand where he has either not paid for the goods, or, paid for the goods and the employee has kept the money received in payment. With the store owner's receipt of the transaction missing at the end of a day's activities, there is no immediate indication that money received for an alleged sale may also be missing. In this way many store owners have been cheated of income from their sales.

One of the most common methods of so cheating an employer is to attempt to retrieve an advanced recorded form ordinarily automatically stored in a locked compartment in an autographic register. After the transaction has been written down on the business form on the register platen and the form has been advanced, the clerk may tear off the original copy, hand it to the customer, and then attempt to pull back the employer's carbon copy which has been advanced into the receiving compartment of the register. Once the employer's carbon copy has been thus retrieved it is torn off and destroyed. Thus, the store owner never receives a copy of an alleged recorded sale.

A primary object of this invention is to provide a novel attachment for an autographic register to detect and prevent tampering therewith.

Another object of this invention is to provide a novel attachment for an autographic register which is responsive to movement imparted to an advanced business form opposite to the normal direction of travel of that business form.

Still another object of this invention is to provide an attachment for an autographic register which will prevent further advancing of recorded business forms once a reverse movement has been imparted to advanced forms.

A further object of this invention is to provide an attachment for an autographic register which will lacerate an advanced business form responsive to an attempt to apply a reverse movement to the advanced business form.

A still further object of this invention is to provide an attachment for an autographic register which will render a register basically inoperative once reverse movement has been attempted to be imparted to an advanced business form.

A yet still further object of this invention is to provide an attachment for an autographic register which, upon the application of reverse movement to an advanced business form, will lacerate the advanced business form, prevent further advancing of business forms and will render the register inoperative until the attachment can be released by access only through a locked closure.

Further objects, features and advantages of the invention will be readily apparent from the following specifications taken with reference to the drawings, in which:

FIGURE 1 is a top plan view of an autographic register which embodies this invention;

FIGURE 2 is a side elevational view of a partial section of the autographic register of FIGURE 1;

2

FIGURE 3 is a fragmentary section view taken along the line 3—3 of FIGURE 1;

FIGURE 4 is a fragmentary section view similar to FIGURE 3;

5 FIGURE 5 is a fragmentary view taken along the line 5—5 of FIGURE 3; and

FIGURE 6 is a section view taken along the line 6—6 of FIGURE 4.

Referring now to the drawings, in FIGURE 1 there is shown a conventional autographic register 10 which embodies the subject matter of this invention. Stationery, for recording business transactions, is indicated generally at 11, and is covered by a top cover 12. A hingedly secured front cover is indicated at 13, and is provided with a lock 14. A handle 15 is provided for turning the main drive shaft 16 which advances recorded business forms. As shown in FIGURE 2, the register 10 is divided into a storage compartment 17 and a front compartment 18, where carbon copies 11a and 11b of advanced forms 11 are received. The front compartment 18 is accessible only through the front cover 13 which is secured by the lock 14.

Referring now to FIGURE 3, the register includes an upper feed roll 19 and a bottom feed roll 20 which cooperate by frictional engagement to advance the recorded business form stationery upon the application of turning movement to the shaft 16. When the register forms have been indexed, or advanced, the original sheet 11 passes out of the register and one or more carbon copies such as 11a and 11b pass into the storage compartment 18. The carbon copies 11a and 11b are guided by a fixed upper guide plate 21 and a hinged front guide plate 22. A curved front extension 23 of the platen 24 defines the lower limits of travel of the carbon copies 11a and 11b.

35 Secured to the front extension 23 of the platen 24 is anti-tampering or anti-retraction or tampering detection device 25 which is the subject matter of this invention. The attachment includes a carrier or mounting means or base 27. Pivotedly secured to the mounting means 27 is 40 a tilting means or gravity weighted carrier 28 which is responsive to reverse movement imparted to the stationery. Attached to the carrier 28 is a paper tearing means or needle 29 which cooperates with the gravity weighted carrier 28 and the guide plate 21 in response to reverse 45 movement imparted to the carbon forms 11a and 11b to lacerate the advanced carbon forms and prevent further reverse movement thereof. Also secured to the mounting means 27 is a spring-loaded plunger 31. In its normal position the plunger 31 acts to keep the gravity weighted carrier 28 in an over balanced position, as shown in FIGURE 3.

The carrier 28 is also provided with an aperture 30. When the attachment has responded to a reverse movement, as shown in FIGURE 4, the frictional engagement 55 and subsequent laceration of the advanced carbon forms of the needle 29 cooperates with the gravity weight of the carrier, causing it to ride over the spring-loaded plunger 31. In so doing, the plunger urges its way into the aperture 30, thereby locking the carrier in the position shown in FIGURE 4. The plunger 31 is carried in a housing 32 and provided with a knob 33 which allows the plunger to be retracted from its normal position. Bearing in mind that all the structure is contained in the compartment 18 which is accessible only through the 60 locked front cover 13, the carrier 28 may be released from its locked position only by disengaging the plunger 31 by means of the knob 33.

The usual method used to cheat a shop owner or employer is to attempt to retrieve the forwarded carbon form of a recorded business transaction. An employee may lift the cover 12 and pull back on the set of forms 11 which are over the platen.

The forwarded carbon copies 11a and 11b located in the locked compartment 13 are physically connected to the lower sheets of the set of forms 11. Therefore, this reverse movement will cause the advanced carbon forms to be pulled back to a position where the employee can locate the particular copy that he is seeking and detach it. Thus the employee may pocket the money received in a transaction, or give away goods to a purchaser who has a receipt for the transaction. With the installation of the present attachment, when a reverse movement is imparted to the advanced form the device takes the position shown in FIGURE 4. The reverse movement causes the needle 29 to catch in the copy forms 11a and 11b and go backward with it. Thus, the device takes the position shown in FIGURE 4 with the weighted carrier secured in its position by the engagement of the plunger 31 through the aperture 30. Also, the needle 29 has pierced the advanced forms 11a and 11b. Further reverse movement causes further laceration of the advanced forms. Also, subsequent advancing proves unsuccessful because the forms are prevented from moving in either direction by the needle 29 and therefore a jam will result. Thus, the device has detected and lacerated the form which was attempted to be destroyed, and has also prevented further operation of the register by the inability to advance it. The register can only be restored to an operable condition by opening the front compartment 13 through the lock 14, the key for which is in the possession of the store owner or employer. The employer may gain access to the compartment and unlock the plunger 31 and restore the carrier 38 to its normal position, but he then knows an attempt has been made to deprive him of the fruits of a transaction, as well as knowing which transaction it was and who was the probable culprit.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. An attachment for an autographic register to prevent tampering with advanced stored forms, comprising: mounting means located adjacent to the path of the forms being fed toward storage; paper tearing means secured to said mounting means, said paper tearing means being movable between a normal position cooperating with the metal parts of the register to define a narrow passage to the storage area for said advanced forms and a paper tearing position blocking passage of the forms past the tearing means; and means for tilting said paper tearing means upon the application of movement to the forms which is opposite the direction of travel of advancing forms, said tilted tearing means being in a position to block said passage and cause laceration of a retracted form whereby further advancing of the forms is prevented and further application of the movement which is opposite to the advancing movement causes additional laceration of the previously advanced forms.

2. An attachment for an autographic register to prevent tampering with advanced business form records of transactions comprising: a paper tearing device mounted adjacent to the path of travel of the forms being fed toward the storage area of said register; said paper tearing device in its normal position cooperating with the metal parts of the register to define a passage to the storage area for said forms; tilting means responsive to motion imparted to said forms which is opposite to the normal direction of travel of said forms, said tilting means when

activated cooperating with said paper tearing means to restrict the passage to the storage area so as to prevent further advance of forms to the storage area; locking means associated with said tilting means to maintain same in its activated position; said locking means and tilting means and paper tearing means cooperating to prevent further advancing of said register and to cause tearing of forms on further retraction thereof; and a locked enclosure in said register enclosing said attachment.

3. An attachment for an autographic register to prevent tampering with advanced business form records of transactions, comprising: a needle mounted in a gravity weighted carrier located adjacent to the path of travel of a business form being fed toward a storage area of said register, said needle having a normal position closely adjacent to the path of said forms; a supporting base secured to the frame of said register and pivotally mounting said carrier; a latch secured to said base and holding said carrier up to maintain said needle to its normal position; said carrier being pivotally responsive to movement imparted to said forms which is opposite to the normal direction of travel of said forms to raise said needle to a position where it intersects the path of travel of said forms; said latch cooperating with said carrier to hold said needle in its intersecting position; and a locked enclosure in said register enclosing said attachment.

4. An attachment for an autographic register to detect tampering with advanced business form records of transactions comprising: a supporting base mounted near the path of travel of said forms and secured to said register; a gravity weighted carrier pivotally mounted on said supporting base; a needle secured to said carrier, said needle in its normal position being adjacent to the path of travel of said forms; a latch mounted in said supporting base and holding said gravity weighted carrier up to maintain said needle in its normal position; said carrier being pivotally responsive to movement imparted to said forms which is opposite to normal direction of travel of said forms to cause said needle to intersect the path of said forms; said latch cooperating with said carrier to maintain said needle in its intersecting position so that advancement of forms is prevented and further opposite movement of said form causes laceration thereof; and a locked closure on the register enclosing said advanced forms and needle.

5. An attachment for an autographic register to detect tampering with advanced business form records of transactions comprising: a supporting base mounted in a path of travel of said forms and secured to said register in an area accessible only through a locked closure; a gravity weighted carrier pivotally mounted on said supporting base; a needle secured to said carrier, said needle having a normal position adjacent to the path of travel of said forms; a latch mounted on said supporting base and holding said gravity weighted carrier up to maintain said needle in its normal position; said carrier being pivotally responsive to movement imparted to said forms which is opposite to the normal direction of travel of said forms to cause said needle to intersect the path of said forms; said latch cooperating with said carrier to maintain said needle in its intersecting position so that advancement of forms is prevented and further opposite movement of said forms causes laceration thereof.
